(57) **CLAIM**

The ornamental design for a combustion tube, as shown and described.

DESCRIPTION

FIG. 1 is a rear elevational view of a combustion tube; FIG. 2 is a right side elevational view thereof; a left side elevational view is identical as the right side elevational view; FIG. 3 is a front elevational view thereof; FIG. 4 is an enlarged detail taken from FIG. 3 thereof; FIG. 5 is a top plan view thereof; and, FIG. 6 is a rear perspective view thereof.
